C. H. WILKINSON

LOOM SHUTTLE

Filed Nov. 16, 1925

Inventor:

Charles Henry Wilkinson.

By his Attorney: Walter Gunn

UNITED STATES PATENT OFFICE.

CHARLES HENRY WILKINSON, OF LEIGH, ENGLAND.

LOOM SHUTTLE.

Application filed November 16, 1925. Serial No. 69,520.

To all whom it may concern:

Be it known that I, CHARLES HENRY WILKINSON, a subject of the King of Great Britain and Ireland, residing at Leigh, Lancashire, England, have invented new and useful Improvements in or Relating to Loom Shuttles, of which the following is a specification.

This invention refers to shuttles for looms and has for its object to provide facilities for threading the shuttles by hand and preventing threading by the mouth.

According to the invention, the shuttle is provided on its top side and at the end 15 usually furnished with the thread eye, with a deep circular depression, large enough to admit the finger of the hand. In one side of the shuttle, and opening into said depression, is a circular hole or opening, which 20 is extended at one side to form a narrow slit, running parallel with the longitudinal axis of the shuttle, the hole and slit forming a key-hole shaped slot. Lying across said slit is a forked pin, or stud, made of 25 metal, porcelain, or other suitable material, the opening of the stud lying in a plane at right angles to the side of the shuttle. One limb of the stud is slightly shorter than the other, and is rounded and slightly turned 30 inwards, and that part of the shuttle into which the lower end of the stud projects, is cupped out or recessed, and is slightly larger than the stud, thereby leaving a 35 space, or clearance, around the lower end of the stud. Extending from the said circular depression to the usual opening for the shuttle tongue, is a groove or channel, through which the weft may pass from the 40 cop.

In threading the shuttle, the weft is drawn off the cop and made into a small tuft or ball, which by means of, say the first or index finger of the weaver's hand, is pushed into the said vertical depression, from which it can be readily drawn by 45 hand through the hole in the side of the shuttle.

On the shuttle being then placed in a loom, the first pick causes the weft thread to pass into the narrow extension of the side hole and slip below the shorter limb of the 50 said forked stud and between the forks of said stud, from which position the weft cannot escape, while free to be drawn out of the shuttle in the weaving operation.

To prevent undue abrasion of the shuttle, a further forked metal, or porcelain, stud, is applied to the groove leading from the cop opening to the said depression, and to provide for a slight drag on the weft, said 60 forked stud has overlapping formations on its inner faces.

The improvements allow of the shuttle being used right or left hand, and for weft way, or twist way, or twist way weft. 65

Upon the accompanying drawing:

Fig. 1 illustrates a side elevation.

Fig. 2 a plan view, and

Fig. 3 a cross section of a shuttle with the invention applied. 70

Figs. 4 and 5 illustrate perspective views of a part of the same shuttle, portions being broken away in Fig. 5 to show the invention more clearly.

Fig. 6 illustrates a detached side view of 75 the forked stud with one limb shorter than the other.

Fig. 7 illustrates a detached side view of the stud used in the groove between the cop opening and depression. 80

Figs. 8 and 9 illustrate in side elevation and plan a modification of such groove stud, while,

Figs. 10 and 11 illustrate like views of a further modification. 85

Fig. 12 illustrates a plan of a modification of Figs. 10 and 11.

a is the body of the shuttle, while *b* is the usual space for the weft cop and *c* the spring tongue. *d* is the large vertical depression extending from the top face of the shuttle to a point below the level of the tongue *c*. *e* is the key-hole shaped opening in the side of the shuttle. *f* is the groove between the depression *d* and the space *b*. In 90 said groove is fitted the forked metal, or porcelain, stud *g*, see Fig. 7, the bifurcations of the stud extending upwards, see Fig. 3, and the inner faces of the bifurcations lying parallel with the sides of the 100 groove, see Fig. 2.

In the top face of the shuttle, near to one side of the shuttle, is formed a recess in which is fitted the forked metal or porcelain, stud *h*, which virtually constitutes the eye of the shuttle, see Fig. 1. Such stud extends across the narrow part of the opening *e*, and its bifurcations extend downwards, see Fig. 1. One limb of the stud is shorter than the other and is slightly bevelled. 110

elled on its outer side and curved inwards, see Fig. 6.

Further, the slot formed by the bifurcations is of key-hole shape, and the round part comes opposite the narrow part of the opening *c*, see Figs. 1, 3 and 4. That part of the shuttle encircling the lower end of the shorter limb of the stud *h* is cut away to form a small cavity and to allow the weft to pass below said shorter limb of the stud when threading the shuttle.

The studs, when made of metal, will preferably be formed in one with a forked extension or bifurcated rivet, whereby the stud may be firmly secured in position (see Fig. 3) with or without the aid of an adhesive. When made of porcelain, the studs will be fixed in position partly by being a tight fit, and partly by means of glue.

In threading the shuttle, a small quantity of weft is drawn off the cop and rolled into a tuft or ball, by which the weft is first laid in the groove *f* and between the bifurcations of the stud *g*. The tuft, or ball, is then inserted by means of the first finger of one hand, into the depression *d*, and pushed down until it comes opposite the opening *c*, when it is nipped by the finger and thumb and pulled through such opening, as shown dotted in Fig. 2. Using the tuft, or ball, as a handle, the weft is then drawn backwards and tensioned with a sharp pull, which causes it to slip below the shorter limb of the stud *h* and pass into the slot formed by the bifurcations of the stud, and finally lie in the round part of the slot, see Figs. 1, 2 and 5, when the shuttle is fully threaded and ready for use. The tensioning of the weft to cause it to pass below the shorter limb of the stud *h* need not be done by the weaver, but may be done automatically in the loom by the first or second pick of the shuttle.

In this way the necessity to thread the shuttle by the mouth is dispensed with, and moreover, the threading of the shuttle by the mouth is prevented, as the holes are too large to allow of the threading being done by suction. After being threaded, the shuttle cannot become unthreaded as the shorter limb of the stud *h*, and the surrounding parts of the shuttle, form an effectual trap.

As a modification the groove stud *g* shown in Figs. 8 and 9 is formed with the bifurcation out of centre and opening tangentially into a central hole. A recess or groove *h* is formed on the front face of the stud leading to the hole. The stud is designed to trap the thread to avoid trouble from coming out by ballooning the thread being caught in the groove *h* should it attempt to rise in the stud.

To afford an additional drag on the weft, the stud *g* may be made as shown in Figs.

10 and 11 or 12, the weft being deflected, or slightly kinked, as it passes through the groove *f*.

What I claim is:

1. A loom shuttle having a large vertical depression extending downwards from the top face of the shuttle near to the usual thread eye position, a key-hole shaped slot in the side of the shuttle with the larger part of the slot opening into said depression, a groove in the top face of the shuttle and extending from the cop space to the said depression, a further vertical depression traversing the narrow part of the said key-hole shaped slot, in combination with a downwardly projecting forked stud in said further vertical depression, one limb of the forked part of the stud being shorter than the other limb and being bevelled and turned inwards at its lower end, the bifurcation forming said forked stud being of key-hole shape and arranged to lie transversely of the shuttle, the shuttle having some of the material around the lower end of the said shorter limb, cut away to allow the weft thread to pass from the slot in the side of the shuttle below the shorter limb of the stud and into the slot thereof, so as to provide a trap as set forth.

2. A loom shuttle having a large vertical depression extending downwards from the top face of the shuttle near to the usual thread eye position, a key-hole shaped slot in the side of the shuttle with the larger part of the slot opening into said depression, a groove in the top face of the shuttle and extending from the cop space to the said depression, a further vertical depression traversing the narrow part of the said key-hole shaped slot, in combination with a drag producing device in said groove and a downwardly projecting forked stud in said further vertical depression, one limb of the forked part of the stud being shorter than the other limb and being bevelled and turned inwards at its lower end, the bifurcation forming said forked stud being of key-hole shape and arranged to lie transversely of the shuttle, the shuttle having some of the material around the lower end of the said shorter limb, cut away to allow the weft thread to pass from the slot in the side of the shuttle below the shorter limb of the stud and into the slot thereof so as to provide a trap, as set forth.

3. A loom shuttle having a large vertical depression extending downwards from the top face of the shuttle near to the usual thread eye position, a key-hole shaped slot in the side of the shuttle with the larger part of the slot opening into said depression, a groove in the top face of the shuttle and extending from the cop space to the said depression, a further vertical depression traversing the narrow part of the said

key-hole shaped slot, in combination with a drag producing forked stud in said groove having overlapping formations on its inner faces, and a downwardly projecting forked stud in said further vertical depression, one limb of the forked part of the stud being shorter than the other limb and being bevelled and turned inwards at its lower end, the bifurcation forming said forked stud 5 being of key-hole shape and arranged to lie transversely of the shuttle, the shuttle having some of the material around the lower end of the said shorter limb, cut away to allow the weft thread to pass from 10 the slot in the side of the shuttle below the shorter limb of the stud and into the slot thereof so as to provide a trap, as set forth.

4. A loom shuttle having a large vertical 20 depression extending downwards from the top face of the shuttle near to the usual thread eye position, a key-hole shaped slot in the side of the shuttle with the larger part of the slot opening into said depression, a groove in the top face of the shuttle 25 and extending from the cop space to the

said depression, a further vertical depression traversing the narrow part of the said key-hole shaped slot, in combination with a drag producing forked stud in said groove 30 having overlapping formation on its inner faces and a forked extension for securing it therein, and a downwardly projecting forked stud in said further vertical depression, one limb of the forked part of the 35 stud being shorter than the other limb and being bevelled and turned inwards at its lower end, the bifurcation forming said forked stud being of key-hole shape and arranged to lie transversely of the shuttle, 40 the shuttle having some of the material around the lower end of the said shorter limb cut away to allow the weft thread to pass from the slot in the side of the shuttle below the shorter limb of the stud and into 45 the slot thereof so as to provide a trap the longer limb being formed with a forked mounting extension, as set forth.

In testimony whereof I have signed my name to this specification.

CHARLES HENRY WILKINSON.
